UNITED STATES PATENT OFFICE.

ALBERT T. HILAMAN, OF NEWARK, DELAWARE.

STOCK REGULATOR FOR PAPER MACHINES.

Application filed November 22, 1920. Serial No. 425,777.

To all whom it may concern:

Be it known that I, ALBERT T. HILAMAN, a citizen of the United States, residing at Newark, in the county of New Castle and 5 State of Delaware, have invented certain new and useful Improvements in Stock Regulators for Paper Machines; and I do declare the following to be a full, clear, and exact description of the invention, such as 10 will enable others skilled in the art to which it appertains to make and use the same.

This invention relates to an improved stock regulator for a paper machine and one 15 object of the invention is to provide a regulator having improved means for movably mounting a hopper receiving the stock from a conveyor spout and improved means for operating a closure at the inlet end of the spout, the actuating means for the closure 20 being connected with the suspending means for the hopper so that when the hopper moves vertically, the closure may be opened or closed according to the direction in which the hopper moves.

25 Another object of the invention is to so construct the supporting or suspending means for the hopper that the hopper and a predetermined amount of stock may be counterbalanced and the hopper thus permitted to move upwardly or downwardly according to whether the amount of stock in 30 the hopper is more or less than the predetermined amount.

Another object of the invention is to so 35 connect the actuating means of the closure with the suspending means of the hopper that the door may be normally held open a predetermined amount and then closed or opened to a greater extent than the hopper 40 moves.

Another object of the invention is to so 45 construct this attachment that it may be used in connection with a conventional type of main box or stock chest and thus permitted to be used in connection with stock chests already in use.

This invention is illustrated in the accompanying drawings, wherein:

Figure 1 is a top plan view of a stock 50 chest having the improved regulator associated therewith.

Figure 2 is a vertical sectional view taken along the line 2—2 of Fig. 1.

Figure 3 is a sectional view taken along 55 the line 3—3 of Fig. 2.

The main box or stock chest 1 is divided by partitions 2 and 3 into an inlet chamber 4, a discharge chamber 5, and an overflow chamber 6, the inlet chamber 4 having an inlet 7, the discharge chamber an outlet 8, 60 and the overflow chamber an outlet 9. The partition 2 is provided with an opening 10 to permit communication between the inlet chamber 4 and the discharge chamber 5 and a conductor spout 11 leads from this opening 10 and is provided with a downturned free end portion which is closed by means of a head 12 and provided with side openings 13 through which the stock will pass. A door or closure 14 is hingedly mounted in 70 the inlet end of the spout 11 for closing the opening 10 and this door is provided with an actuating rod 15 which extends through an opening 16 in the spout 11.

A hopper 17 which is conical and open at 75 its lower and upper ends is positioned in the discharge chamber beneath the outlet end of the spout 11 and provided at its upper end with an outstanding collar 18 having openings formed therein to receive the 80 hanger rods or bolts 19. These rods 19 extend through openings formed in the pan 20 positioned beneath the lower end of the hopper and forming a closure for the lower end of the hopper and further forming a 85 baffle which will control the passage of stock out of the hopper when the device is in operation. This hopper is positioned as shown in Fig. 2 and a water pipe 21 extends down into the discharge chamber and carries a 90 circular spraying head 22 which is positioned about the outlet end portion of the spout 11 within the upper portion of the hopper so that the water from the spraying head will be sprayed upon the walls of the 95 hopper and thus permit the stock to be washed out of the hopper.

In order to suspend the hopper there has been provided a frame having crane arms 23 which are mounted upon a rocker shaft 24 100 journaled in the bearing brackets 25 secured to the walls of the discharge chamber. These crane arms extend above the inlet chamber and carry weights 26 which are adjustably mounted and held in place by set 105 screws 27 so that the weights can be properly placed. The crane arms have their end portions above the discharge chamber forked and pivotally connected with hanger rods 28 which are secured to the hopper by 110

rivets or other suitable fasteners and will thus cause the hopper to be suspended in a vertical position beneath the outlet end of the spout. A cross bar 29 extends between 5 the crane arms 23 and has its end portions journaled in bearing plates 30 which are secured by bolts or other removable fasteners which pass through slots 31 formed in the crane arms. The actuating rod 15 extends 10 through an opening formed in the cross bar 29 and winged nuts 32 are carried by the actuating rod for engaging the upper and lower portions of the cross bar and thus securely but releasably holding the actuating 15 rod in a set position. It will thus be seen that by releasing the fasteners for the bearing plates, the cross bar may be moved longitudinally of the crane arm and the door thus placed in the desired position with the 20 hopper suspended at the proper point of elevation.

When the hopper is in use, it will be filled to a certain extent with the stock and in order to permit the hopper to be properly counterbalanced and yieldably held at 25 a predetermined point of elevation, there has been provided an addition to the adjustable weights 26, a weight holder 33 which is carried by a line 34 which line 30 passes over a pulley wheel 35 carried by the brackets 36 and is then carried over the inlet chamber 4 and connected with the upper end of a substantially V-shaped lever or turning handle 37. This turning handle 35 or lever has its arms provided with bearing heads 38 which fit upon the rocker shaft 24 and will be secured by set screws 39. By placing the proper number of weights 40 upon the weight holder 33, the hopper 40 with a predetermined quantity of stock therein may be counterbalanced and held at the proper point of elevation. If the amount of stock in the hopper falls below the desired amount, the hopper will be 45 drawn upwardly and this will cause the rods 15 to draw upon the door and thus swing the door open to permit a greater quantity of stock to pass through the spout 11. If on the other hand, the stock is flowing 50 into the hopper faster than desired, the hopper will be filled beyond the desired amount and this will provide sufficient weight to cause the hopper to move downwardly. When the hopper moves downwardly, the rods 15 will force the door 14 towards a closed position thus cutting off 55 the flow of stock through the opening 10 and preventing the stock from feeding too rapidly through the spout. It will thus be seen that the stock controlled device, will 60 be automatic in its operation when the cross bar 29 and rods 15 are adjusted to the proper point and the weights 26 have been adjusted upon the extended end portions 65 of the crane arms and the proper number

of weights placed upon the weight holder 33. By proper adjustment of the rods 15 through the medium of the winged nuts 41, the tray 20 can be positioned the desired distance away from the open lower end of 70 the hopper and the stock permitted to flow freely or be restricted in its flow. A stock control has thus been provided which is simple in operation and which can be associated with stock chests of a conventional 75 construction already in use.

I claim:

1. A stock regulator comprising a tank having a partition therein dividing the tank into a receiving compartment and a discharge compartment, the partition having an opening for communication between the compartments, a spout leading from the opening and having a closed end provided with side openings, a rocker shaft extending 85 above the partition, weighted crane arms carried by said rocker shaft, a supporting rod extending between the crane arms and adjustably connected therewith, a closure for the opening in the partition hingedly 90 mounted in the spout, an actuating rod engaging the closure and adjustably connected with the supporting rod, a hopper positioned in the discharge chamber beneath the spout and having an open lower end, a pan 95 beneath the open lower end of the hopper, supporting rods for the pan adjustably connected with the hopper, suspending rods for the hopper pivotally connected with said crane arms, and weighted means connected with the rocker shaft to counterbalance the hopper and contents thereof.

2. A stock regulator comprising a tank, a partition dividing the tank into a receiving chamber and a discharge chamber and 105 having an opening for communication between the chambers, a spout in the discharge chamber leading from the opening in said partition, a movable closure for the opening positioned in the spout, an open ended hopper in the discharge chamber beneath the spout, a pan adjustably supported beneath said hopper for movement towards and away from the open lower end thereof, and supporting and actuating means for 110 the hopper and closure comprising a rocker shaft, crane arms carried by said rocker shaft, hanger links suspending the hopper from said crane arms, a cross-rod extending between and adjustably connected with 115 said crane arms, and a rod pivotally connected with the closure and adjustably connected with said cross-rod.

3. A stock regulator comprising a tank having a partition therein dividing the tank into a receiving compartment and a discharge compartment, the partition having an opening for communication between the compartments, a spout leading from the opening, a rocker shaft, crane arms carried 125

130

by said rocker shaft, a supporting rod extending between the crane arms, a movably mounted closure for the opening in the partition, an actuating rod engaging the closure and connected with the supporting rod, a hopper positioned in the discharge chamber beneath the spout and having an open lower end, a pan beneath the open lower end of the hopper, supporting rods for the pan adjustably connected with the hopper, and means for suspending the hopper from said crank arms.

4. A stock regulator including a conductor spout, a movable closure for the inlet end of said spout, a rocker shaft, arms extending from said rocker shaft, an open ended hopper suspended from the arms and positioned beneath the outlet end of said

spout, a pan adjustably mounted beneath the hopper for receiving material from the same and closing the open lower end of the hopper when moved into engagement with the lower end thereof, a cross bar carried by said arms, and an actuating rod for said closure connected with said cross bar for moving the closure to close the inlet end of the spout when the hopper moves downwardly.

In testimony whereof I have hereunto set my hand in the presence of two subscribing witnesses.

ALBERT T. HILAMAN.
